(57) **CLAIM**

The ornamental design for a toilet plunger, as shown and described.

DESCRIPTION

FIG. 1 is a first perspective view of a toilet plunger showing my new design;

FIG. 2 is a second perspective view of the toilet plunger of FIG. 1;

FIG. 3 is a front view of the toilet plunger of FIG. 1;

FIG. 4 is a back view of the toilet plunger of FIG. 1;

FIG. 5 is a first side view of the toilet plunger of FIG. 1;

FIG. 6 is a second side view of the toilet plunger of FIG. 1;

FIG. 7 is a top view of the toilet plunger of FIG. 1; and,

FIG. 8 is a bottom view of the toilet plunger of FIG. 1.

The broken lines illustrate portions of the toilet plunger and form no part of the claimed design.

1 Claim, 7 Drawing Sheets
